BAG SEALING MACHINE

August E. Almgren, Hillside, and John P. Jakob, Roselle, N. J., assignors to American Can Company, New York, N. Y., a corporation of New Jersey

Application December 17, 1947, Serial No. 792,123

11 Claims. (Cl. 53—150)

1 The present invention relates to a machine for sealing filled paper bags and other flexible containers and has particular reference to devices for receiving a filled bag and for turning it into and through predetermined positions incidental to effecting the sealing of the bag and its discharge from the machine. This is a companion application to our copending United States applications Serial Number 792,122, filed December 17, 1947, on Sealing Head Mechanism for Closing and Sealing Bags and Containers; Serial Number 792,124, filed December 17, 1947, on Bag Sealing Machine; and Serial Number 792,125, filed December 17, 1947, on Method of Sealing Bags.

In the usual factory method of can making, empty cans immediately upon manufacture are packed into large paper bags or other suitable flexible containers for protection against contamination during shipment and storage. The cans are placed in the bags manually or by machine and in either case are arranged in orderly rows and layers so that a substantially firm and solid package results when the bag is filled and closed.

In packing the cans into the bag, it has been found that for best results, the bag should be held in a horizontal or slightly inclined position from the horizontal so that the cans may be handled horizontally or substantially so. However, in this horizontal filling position the bag is difficult to seal. For this reason, the bag when filled usually is turned into an upright position for sealing. The filled bag is handled manually for effecting these operations.

The instant invention contemplates the provision of a machine for automatically handling and sealing the filled bag.

An object of the invention is the provision of a single station machine for sealing filled bags or other flexible containers which machine is of simple and economical construction and is well adapted to quickly turn a filled bag through a plurality of working positions incidental to positioning the bag for sealing and for handling the sealed bag during its discharge from the machine.

Another object is the provision of such a simple machine wherein a bag sealing mechanism may be readily incorporated in the machine so that sealing of the bag as well as handling it may be effected in the same machine, thereby eliminating unnecessary transfers and extra handling of the bag.

Numerous other objects and advantages of the invention will be apparent as it is better under-

2 stood from the following description, which, taken in connection with the accompanying drawings, discloses a preferred embodiment thereof.

5 Referring to the drawings:

Figure 1 is a side elevation of a bag closing and sealing machine embodying the present invention; with parts broken away;

Fig. 2 is a view similar to Fig. 1 illustrating 10 the lower portion of the machine with parts shown in a different position and with parts broken away;

Fig. 3 is a front view of the lower portion of 15 the machine as viewed from the left in Fig. 1, with parts broken away;

Fig. 4 is a top plan view of the lower portion of the machine illustrated in Fig. 2, with parts broken away;

Fig. 5 is an enlarged perspective view illustrating 20 the upper open end of a bag filled with cans preparatory to being sealed in the machine shown in Fig. 1;

Fig. 6 is a view similar to Fig. 5 showing the bag closed and sealed;

25 Figs. 7, 8 and 9 are enlarged perspective views showing a corner of a bag and illustrating how the marginal corner and marginal side section are folded into sealing position;

Fig. 10 is an enlarged sectional view showing 30 a pleated corner fold taken substantially along the line 10—10 in Fig. 6;

Fig. 11 is an enlarged top plan view of a sealing head mechanism shown in Fig. 1;

Fig. 12 is a sectional view taken substantially 35 along the line 12—12 in Fig. 11 and showing the sealing head in position for sealing the open end of a filled bag, with parts broken away;

Fig. 13 is an enlarged side elevation of machine control devices located at the upper right hand corner of the machine shown in Fig. 1, with parts broken away and parts in section;

Fig. 14 is a sectional view of the control devices shown in Fig. 13 the view being taken substantially along the line 14—14 in that figure, and including an electric wiring diagram;

Fig. 15 is a sectional view taken substantially along the line 15—15 in Fig. 14;

Fig. 16 is a schematic perspective view showing the control devices and showing a piping diagram for fluid operated devices for actuating the sealing head mechanism, with parts broken away;

Fig. 17 is an enlarged sectional detail of one of a plurality of fluid slide valves included in the control devices shown in Fig. 16 with parts broken away; and

Fig. 18 is an enlarged sectional detail of one of a plurality of the fluid operated devices shown in Fig. 16, with parts broken away.

As a preferred embodiment of the invention the drawings illustrate a sealing machine arranged to receive a bag or flexible container A (Fig. 5) filled with empty cans B, for sealing. The bag is received in a position slightly inclined to the horizontal (Fig. 2), which is the filling position ordinarily used in can packing practice as hereinbefore mentioned, and is first turned into an upright position and is then sealed. Following this sealing operation the sealed bag is rotated into an angular position for discharge from the machine.

The bag A preferably is made of fibre material and in general is of a rectangular configuration as best shown in Figs. 5 and 6. When the bag is filled with cans, a marginal edge portion C of the bag extends beyond the top layer of cans a distance sufficient to permit folding of this portion inwardly against a flat sheet or closure member D for completely closing and sealing the bag. The closure member is inserted manually after the bag is filled. This closure member is provided with a band of adhesive or glue E on its outer surface, adjacent but in spaced relation to its outer periphery, for securing the folded portion of the bag to the closure member.

In the machine, a filled bag A to be sealed is received from any suitable source of supply, in a rectangular shaped, sheet metal carrier or cradle 21 (Figs. 1 and 2) having a bottom 22, fixed side and back walls 23, 24 respectively, a hingeable side wall 25, and a hingeable front wall 26. The top of the cradle is open. The hingeable side wall 25 and front wall 26 are connected by hinges 27 to the bottom 22 to permit outward movement of these walls to expand the open end or mouth of the cradle to facilitate reception of a filled bag A.

The front wall 26 may be retained in a partially open position as shown in Fig. 2 or may be locked in a closed position as shown in Fig. 1. When in a partially open position it is held by a pair of latch members 29. The inner ends of these members are connected to the cradle 21 by large headed buttons 31 which extend through elongated slots 32 in the members and are welded or riveted to the side walls 23, 25 of the cradle. The outer ends of the members are formed with notches 34 which are engageable with pins 35 secured in the front wall 26 of the cradle. Stop pins 36 on the side walls 23, 25 on both sides of the latch members limit the swinging movement of the members.

Locking of the front wall 26 in a closed position is effected preferably by a manually operable handle 38 (Fig. 2) which is mounted on a pivot pin 39 secured to the cradle side wall 23. The handle is formed with a hook 41 for engagement over a pin 42 secured in the front wall 26. The handle also carries a pivotally mounted arm 43 which is backed up by a spring 44 on the handle and which is operable against a movable element 45 of an electric switch 46 mounted on the cradle side wall 23. The switch is used for starting the machine when the cradle front wall 26 is closed as will be more fully explained hereinafter.

The cradle 21 is rotatable for turning a received bag A into a plurality of positions for receiving, sealing and discharging the bag A as hereinbefore mentioned. For this purpose the cradle 21 is mounted on a U-shaped yoke or bracket 51 (Figs. 1, 2, 3 and 4) which is secured

to the bottom of the cradle. The upright legs of the yoke extend up adjacent the side walls of the cradle. One leg is secured to the fixed side wall 23. The other leg which is disposed adjacent the side wall 25 is spaced away from the wall to permit opening of this wall and serves as a stop for limiting the travel of the wall.

The upper ends of the yoke 51 carry pivot pins 52 which are rotatably mounted in the upper ends of a U-shaped support bracket 53 disposed adjacent the yoke 51. The support bracket 53 is mounted on the outer ends of a pair of spaced and parallel movable rails 54 which at their inner ends and intermediate their ends are pivotally carried on two pairs of parallelogram links 55. The upper ends of the four links are carried on pivot pins 57 secured in a frame 58 having a base plate 59 and which constitutes the main frame of the machine.

The cradle 21 is connected to the frame 58 by a curved tilting or actuating link 61. One end of the link is mounted on a pivot pin 62 secured in the frame. The opposite end of the link is mounted on a pivot pin 63 secured in a lug 64 which extends down from the bottom of the cradle adjacent its front wall 26.

The rails 54 are shifted through an outward stroke and a return stroke for tilting or rotating the cradle 21 into desired positions as will be explained hereinafter. For this purpose the rails carry a cross-shaft 66 having an arm 67, the outer end of which is pivotally connected to a piston rod 68 carrying a piston operating in a cylinder 69 bolted to the base 59 of the main frame 58. Compressed air or other suitable fluid is introduced into the cylinder by way of tubes 71, 72 which are connected to the cylinder at each end thereof and which communicate with the interior of the cylinder.

The fluid tubes 71, 72 lead to and are connected into a control valve 73 (Figs. 16 and 17) having a bore 74 containing a slideable valve plunger 75. The ends of the plunger extend beyond the valve 73 and are formed with longitudinal vent channels 76, 77 which communicate with the outside atmosphere. Intermediate its ends the plunger is formed with an annular channel 78 which at all times communicates with an inlet tube 79 secured in the valve 73. This inlet tube leads to a suitable supply of compressed air or other fluid.

The normal position of the valve plunger 75 in its valve 73 is shown in Fig. 17. In this position the lower end of the plunger blocks off communication between the tube 71 and the inlet tube 79 and vents the tube 71 and the cylinder 69 on one side of the piston, to the outside atmosphere by way of the plunger vent 76. The tube 72 is in communication with the inlet pipe 79 and therefore is conveying fluid under pressure to the cylinder on the opposite side of the piston. The vent 71 is out of register with the tube 72.

The plunger 75 is yieldably retained in this normal position by a spring 81 which is interposed between the outer end of the plunger and a retaining strap 82 secured to the valve. This spring presses the inner end of the plunger against a rotatable edge cam 85 which constitutes a member of a control mechanism 86. The cam 86 is mounted on a normally stationary sleeve 87 (Fig. 14) carried on a continuously rotating shaft 88 journaled in a plurality of bearings 89 formed on a control bracket 91 secured to the main frame 58 at its upper end.

The shaft 88 is rotated by a worm wheel 92

which meshes with a worm 93 carried on a continuously rotating drive shaft 94 journaled in a bearing 95 formed on the control bracket 91. The drive shaft is rotated in any suitable manner. The worm wheel 92 is formed with the outer shell or driving member 97 of a conventional one revolution clutch which surrounds a normally stationary driven member 98 formed on the cam sleeve 81. The driving member is formed with a driving notch 99 (Fig. 15) which is adapted to be engaged by a dog 101 located in a recess 102 in the driven member 98 and pivotally mounted in the member. The dog is backed up by a spring barrel 103 located in the driven member 98.

The clutch dog 101 is normally held within the recess 102 of the driven member 98 by an upright flapper 105 mounted on a pivot pin 106 carried in lugs 107 formed on the control bracket 91. The lower end of the flapper is pivotally connected to a movable element 111 of a normally de-energized electric solenoid 112 bolted to the control bracket 91. The solenoid is connected by wires 114, 115 respectively to the cradle handle switch 46 and to a source of electric current such as a generator 116 (see wiring diagram in Fig. 14). The generator and the switch are connected by a wire 117.

At the beginning of a cycle of operation of the machine with the parts of the machine thus far explained in their normal positions, the cradle support rails 54 are in an extended position similar to that shown in Fig. 2 and the cradle 21 is in a nearly horizontal position with its front wall 26 engaged by the latches 29 as shown in Fig. 2. The front wall 26 and the hinged side wall 25 are open. It is in this position of the cradle that a filled bag A is inserted into it, the bag resting on the open front wall 26. The bag may be inserted manually or by a machine that fills the bag, as the case may be.

When the bag A is fully in the cradle 21, the open side wall 25 of the cradle is closed and then the front wall 26 is hinged into closed position and locked by the handle 38. The outer edges of the front wall 26 are formed with inwardly extending flanges 118 (see Fig. 4) which engage over the marginal edge portions of the fixed wall 23 and the hinged wall 25 of the cradle to hold the hinged wall in closed position when the front wall is locked shut. With these two movable walls of the cradle locked shut the bag A within the cradle is confined against displacement.

Locking of the front wall 26 of the cradle in a closed position requires rotation of the handle 38. During this rotation of the handle, its arm 43 pushes the movable element 45 of the electric switch 46 and thus closes the switch. This is only a momentary action, the arm 43 immediately snapping past the switch element 45 as shown in Fig. 1 and thereby releasing it to again open the switch. The switch is thus closed only on a locking movement of the handle so that it cannot again be closed when the handle is shifted to open the cradle.

The momentary closing of the switch 46 temporarily energizes the solenoid 112 of the control mechanism 86 and this shifts the flapper 105 of the one revolution clutch, to one side of the dog 101 and thus releases the dog. The released dog is forced outwardly by its spring barrel 103 and thus engages in the notch 99 of the constantly rotating drive member 97. This engagement of the dog with the notch connects the drive member 97 to the driven member 98 for one revolution of the clutch and thus rotates the cam 85 through 75

one revolution. During this revolution of the clutch, the solenoid becomes de-energized and thus pushes the flapper back into position to re-engage the dog and withdraw it from the notch at the end of the one revolution. The driven member 98, its sleeve 81, and the cam 85 carried thereon stop rotating immediately and thus terminates the one cycle of operation of the machine.

10 During the rotation of the cam 85, it shifts the valve plunger 75 (Fig. 17) to cut off communication between the tube 72 and the inlet tube 79 and to bring the tube 71 into communication with the inlet tube. The tube 72 is also vented by the vent 77, and the vent 76 is cut off. This permits fluid from the inlet tube 79 to flow through the tube 71 and into the cylinder 69 in front of its piston and thereby push the piston toward the outer end of the cylinder (toward the right as viewed in Fig. 2).

15 This movement of the piston swings the cradle support rails 54 on their links 55 and thus draws them inwardly and downwardly into the position shown in Fig. 1. During this movement of the rails, 25 the curved link 61 attached to the cradle, pivots or rotates the cradle 21 on its pivot pins 52 into the upright position shown in Fig. 1. The filled bag A is now in an upright position with its open top end uppermost and ready for sealing. The 30 fluid acting against the piston in the cylinder 69 keeps the cradle in this position during the sealing operation. This positioning of the bag requires only a portion of the one revolution cycle of the machine, the remaining portions being 35 devoted to sealing and discharging the bag.

20 Sealing of the bag is effected preferably by a vertically movable sealing head 121 (Figs. 1, 11 and 12) which is disposed in a position directly above the uprighted cradle 21 and the bag A contained therein. The head includes a hollow rectangular shaped head frame 122 which is supported on a pair of spaced and parallel support links 123 and an actuating lever 124. The links and the lever form a parallelogram system of 40 support which maintains the head in a level position while permitting vertical travel.

25 The outer ends of the support links 123 are mounted on trunnions 125 formed on an inverted U-shaped bracket 126 which is secured to the head frame 122 and which extends across the top of the frame. The inner ends of the links are mounted on pivot pins 127 secured in the machine frame 58.

30 The outer end of the actuating lever 124 is mounted on a pivot pin 129 carried in a pair of spaced upright lugs 131 formed on the frame bracket 126. Intermediate its ends the lever is mounted on a pivot pin 132 carried in spaced upright lugs 133 formed on the machine frame 58.

35 Vertical movement of the sealing head 121 is effected by the actuating lever 124. For this purpose the lever extends back through an opening 134 in the machine frame, and at this end carries a link 135 which is pivotally connected to a piston rod 136 having a piston which operates within a vertically disposed cylinder 137 secured to the machine frame 58. The ends of the cylinder are connected by tubes 141, 142 to a valve 143 (Fig. 16) which is similar to the valve 73 and which is connected to the fluid inlet tube 79. This valve 143 is located adjacent the valve 73 and is actuated by an edge cam 144 mounted adjacent the cam 85 on the cam sleeve 81, to connect the tubes 141, 142 alternately with the inlet tube 79.

Hence when the cam sleeve 87 rotates through its one revolution cycle, as hereinbefore explained, it rotates the cam 144 in time with the cam 85 and thus during this cycle and at the proper time, actuates the valve 143 to admit fluid into the lower end of the cylinder 137 and to vent its upper end. This fluid pushes the piston and the rod 136 upwardly and thus rocks the actuating lever 124 on its pivot 132. Rocking of the lever 124 moves the sealing head 121 down on top of the open end of the bag as shown in Fig. 12.

Downward travel of the sealing head 121 is limited by an adjustable set screw 145 (Fig. 1) which is threadedly secured in a lug 146 on the machine frame 58 and which is engageable against a boss 147 formed on the actuating lever 124. This screw locates the head in a proper position on the bag. A tapered hood 148 (Figs. 1 and 12) secured to the bottom of the head frame 122 guides the upstanding marginal edge portion C of the bag A into the head as the latter moves down over it for the sealing operation and thereby prevents crushing or distortion of this portion of the bag. After the sealing operation the head 121 is raised to its normal elevated position as shown in Fig. 1, by the action of the cam 144 on its valve 143, permitting fluid to enter the cylinder 137 through the tube 142 while venting the tube 141.

While the sealing head 121 is in sealing position on the open end of the bag A, it folds the upstanding marginal edge portion C of the bag inwardly and downwardly against the adhesive coated portions of the closure member D and thus seals the bag. This folding operation preferably is effected in two stages, a corner folding stage and a side folding stage, to produce a neat appearing fold as best shown in Fig. 6.

Folding of the corners of the upstanding marginal edge portion C is brought about by four triangular shaped corner folding elements 151 (Figs. 7, 8, 9 and 11) which are located one at each corner of the head frame 122 and which are normally in an upright position. These elements are mounted on pivot pins 152 carried in pairs of spaced lugs 153 which project downwardly from the inside of the head frame at its corners. Each folding element is formed with a pair of spaced actuating arms 155 which are pivotally connected to the lower end of a link 156. The upper end of the link is connected to a piston rod 157 (Figs. 16 and 18) having a piston 158 which operates in a cylinder 159. There are four of these cylinders and they are located one at each corner of the head frame 122 and are secured to the frame as shown in Fig. 18.

All four of the corner cylinders 159 (Fig. 16) are connected at their upper ends to and are in communication with a fluid supply pipe 161 having a lead pipe 162 connected by a flexible tube 163 to a valve 164 which is similar to the valve 73 (Fig. 17) and which is located adjacent the valve 143.

The lower ends of the cylinders 159 are connected by and are in communication with a fluid supply pipe 165 having a lead pipe 166 connected by a flexible tube 167 to the valve 164. The valve 164 like the other valves 73, 143 is connected to the fluid inlet tube 79 and is operated to bring the supply pipes 161, 166 alternately into communication with the inlet tube 79. Actuation of the valve 164 is brought about by an edge cam 168 which is mounted on the cam sleeve 87 adjacent the head actuating cam 144 as shown in Fig. 16 and is rotated by this sleeve.

Hence during the one revolution cycle of the cam sleeve 87, as hereinbefore explained, the edge cam 168 actuates the valve 164 to permit fluid from the main inlet tube 79 to flow through the lower supply pipe 165 while venting the upper supply pipe 161 and to enter all of the corner cylinders 159 simultaneously, below the pistons 158. This fluid pushes the pistons up and thereby simultaneously rocks all of the corner folding elements 151 inwardly and downwardly against the corners of the upstanding marginal edge portion C of the bag to be sealed, as best shown in Fig. 7.

This action of the corner folding elements 151 folds the corners of the marginal edge portion C inwardly and downwardly against the adhesive coated portion of the closure member D in the top of the bag. The corner elements 151 hold these corner sections in this folded position while the side portions of the marginal edge portion C are folded inwardly in a similar manner as will now be explained.

The side portions of the marginal edge portion C are folded into place by a plurality of side folding elements 171 which are normally disposed in an upright position. These side folding elements 171 are located inside the head frame 122 and extend along the sides of the bag A to be sealed, from one corner element 151 to the other. Each side folding element 171 is formed with a pair of spaced lugs 172 carried in a bracket 174 secured to the inner face of the head frame 122.

The side folding elements 171 are hinged toward and away from the bag A to be sealed by arms 176 which are secured to the folding elements. There is one arm for each folding element. The outer end of each arm 176 is pivotally connected to an upright link 177, the upper end of which is pivotally connected to a piston rod 178 of a cylinder 179 (see Fig. 16) carried on the head frame 122. There is one cylinder 179 for each folding element. These cylinders are similar in construction and operation to the corner folding cylinders 159 shown in Fig. 18.

The upper ends of all of the side folding cylinders 179 are connected by and are in communication with a fluid supply pipe 181 (Fig. 16) having a lead pipe 182 connected by a flexible tube 183 to a valve 184 which is similar to the valve 73 (Fig. 17) and which is located adjacent the valve 164. The lower ends of the cylinders 179 are connected by and are in communication with a fluid supply pipe 185 having a lead pipe 186 connected by a flexible tube 187 to the valve 184. The valve 184 like the other valves 73, 143, 164 is connected to the fluid inlet tube 79 and is operated to bring the supply pipes 181, 185 alternately into communication with the inlet tube 79. Actuation of the valve 184 is brought about by an edge cam 188 which is mounted on the cam sleeve 87 adjacent the corner folding element actuating cam 168 as shown in Fig. 16 and is rotated by this sleeve.

Hence during the one revolution cycle of the cam sleeve 87, as hereinbefore explained, the edge cam 188 actuates the valve 184 to permit fluid from the inlet tube 79 to flow through the lower supply pipe 185, while venting the upper supply pipe 181, and to enter all of the side folding cylinders 179 simultaneously, below the pistons in the cylinders. This fluid pushes the pistons up and thereby simultaneously rocks all of the side folding elements 171 inwardly and downwardly against the upstanding marginal edge portion C

of the bag to be sealed, as best shown in Fig. 8. This action of the side folding elements 171 folds the sides of the marginal edge portion C inwardly and downwardly against the adhesive coated portion of the closure member D in the top of the bag.

While the side folding elements 171 temporarily hold down the folded over side portions of the marginal edge portion C, the corner folding elements 151 are quickly lifted as shown in Fig. 9 to release their hold on the folded over corners of the edge portion C. This permits the folded over side portions, adjacent the corner portions to overlap the corner portions as shown in Fig. 9. The corner elements 151 are immediately pressed down again to crease these overlapping sections of the side portions to provide a neat appearing corner fold as best shown in Fig. 10. This action of the corner folding elements is brought about by the cam 168 during its operation of the valve 164.

While the folded over sections of marginal edge portion C of the bag are temporarily held in place by the corner folding elements 151 and the side folding elements 171, the inner edges of this portion are pressed down against the closure member D to complete the sealing of the bag. This is brought about by a rectangular shaped sealing pad 191 (Figs. 11 and 12) which is disposed in the sealing head 121 and which is of proper proportions to fit within the outline defined by the inner edges of the closed corner and side folding elements 151, 171 respectively.

The sealing pad 191 is normally held in suspension within the head by a pair of vertical spaced and parallel rods 192 (Figs. 11 and 12). The lower ends of the rods are secured in bosses 193 formed on the pad. These rods extend up through a pair of slide bearings 194 formed in the bracket 126 and at their upper ends carry locknuts 195 threadedly secured thereto. Compression springs 196 surrounding the rods and interposed between the slide bearings 194 and the locknuts 195, retain the sealing pad in yieldable suspension.

The sealing pad 191 is moved down into engagement with the bag A, by a pair of edge cams 198 which operate against a pair of spaced cam rollers 199 carried in lugs 201 formed on the sealing pad. The cams are mounted on a cross-shaft 202, the ends of which are carried in bearings 203 formed in the upright portions of the bracket 126. The shaft is oscillated at the proper time by an arm 205 (see also Fig. 1) which is mounted on the shaft. The outer end of the arm is connected by a link 206 to a piston rod 207 having a piston operating in a sealing pad air cylinder 208 which is secured to the bracket 126 and which is similar to the cylinder 159 shown in Fig. 18.

The upper end of the cylinder 208 is in communication with and is connected by a flexible tube 211 to a valve 212 (Fig. 16) which is similar to the valve 73 shown in Fig. 17 and which is disposed adjacent the valve 184. The lower end of the cylinder 208 is in communication with and is connected by a flexible tube 213 to the valve 212. The valve like the other valves 73, 143, 164, 184 is connected to the fluid inlet tube 79 and is operated to bring the tubes 211, 213 alternately into communication with the inlet tube 79. Actuation of the valve 212 is brought about by an edge cam 215 which is mounted on the cam sleeve 87 adjacent the side folding element actuating cam

188 as shown in Fig. 16 and is rotated by the sleeve.

Hence during the one revolution cycle of the cam sleeve 87, as hereinbefore explained, the edge cam 215 actuates the valve 212 to permit fluid from the inlet tube 79 to flow through the upper flexible tube 211, while venting the lower tube 213, to lower the sealing pad 191 into sealing position on top of the bag as hereinbefore explained. The pad is pressed down tightly to effect the sealing operation and is then lifted along with the head 121 to permit discharge of the sealed bag. The corner and the side folding elements 151, 171 are also hinged into an upright position in readiness for the next bag. This raising of the pad, the head, and the folding elements is effected by their cams 215, 144, 168, 188 and their respective valves 212, 143, 164, 184 to permit the flow of fluid in the opposite direction, into the cylinders connected with these valves.

When the head 121 is clear of the sealed bag, the cradle 21 is tilted forward into the inclined position shown in Fig. 2 to permit the removal of the bag. This removal of the bag may be effected manually. Tilting of the cradle 21 is effected by its cam 85 as the cam sleeve 87 approaches the end of its one revolution cycle. The cam actuates its valve 73 to open communication between the fluid supply tube 72 and the inlet tube 79 while venting the tube 71 by way of the vent 76 (Fig. 17) in the valve plunger 75. Fluid thereby flows into the cylinder 69 in back of its piston and thus pushes the cradle support bars 54 outwardly. This movement of the bars tilts the cradle. The cradle is held in this tilted position by a stop member 218 which is secured to the bracket 53 and which engages against the bracket 51 (Fig. 2).

Upon tilting of the cradle into position for removal of the sealed bag, the flapper 105 (Fig. 15) of the one revolution clutch, engages the driving dog 101 and presses it back into its recess 102 of the clutch driven member 98 and this releases this member from the driving member 97. The cam sleeve 87 thereupon stops rotating. This completes the cycle of operation of the machine.

When the cradle 21 is in position for removal of the bag, the handle 38 is shifted to unlock the front wall 26, and the latches 29 are lifted to release them from their pins 35. The front wall 26 thereupon falls into the position shown in dotted lines in Fig. 2 and permits the sealed bag to fall out of the cradle.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

We claim:

1. In a machine for sealing a bag or other flexible container filled with articles, the combination of a movable support, a cradle carried on said support for receiving and holding a filled bag to be sealed, said cradle having a movable side wall expandable to receive and contractible to hold a bag in said cradle, means operable against said cradle through the movement of said support for shifting said cradle into different positions including positions for receiving, sealing and discharging said filled bag, actuat-

ing means for moving said support, locking means on said cradle for locking said movable wall in contracted position, and starting means engaged by said locking means when the wall is moved into contracted bag holding position for starting said actuating means.

2. In a machine for sealing a bag or other flexible container filled with articles, the combination of a frame, a support movably mounted on said frame, a cradle pivotally carried on said support for receiving and holding a filled bag to be sealed, and a tilting link having one end connected with said cradle and having its opposite end movably anchored to said frame for tilting said cradle into different positions including bag receiving, sealing and discharging positions through the movement of said support.

3. In a machine for sealing a bag or other flexible container filled with articles, the combination of a frame, a plurality of parallelogram links pivotally carried on said frame, a movable support member carried on said parallelogram links, a cradle pivotally mounted on said support for receiving and holding a filled bag to be sealed, and a tilting link connecting with said cradle and said frame for tilting said cradle with the movement of said support member into a plurality of positions including bag receiving, sealing and discharging positions.

4. In a machine for sealing a bag or other flexible container filling with articles, the combination of a frame, a support movably mounted on said frame, a cradle pivotally carried on said support for receiving and holding a filled bag to be sealed, a tilting link connecting with said cradle and said frame, means operable against said cradle through the movement of said support and under control of said tilting link for shifting said cradle into various positions including positions for receiving, sealing and discharging said filled bag, and actuating means for shifting said movable support into positions determined by the required positions of said cradle.

5. In a machine for sealing a bag or other flexible container filled with articles, the combination of a movable support, a cradle carried on said support for receiving and holding a filled bag to be sealed, means operable against said cradle through the movement of said support for shifting said cradle into various positions including positions for receiving, sealing and discharging said filled bag, a support actuating cylinder having a fluid actuated member for shifting said movable support into positions determined by the required positions of said cradle, a sealing head unit comprising folding and sealing elements movable relative to the open end of a bag in said cradle for sealing the bag when the cradle is in its sealing position, sealing head actuating cylinders having fluid actuated members for moving said sealing head unit into sealing position on said bag and for operating said folding and sealing elements, and control mechanism for timing the operations of said support actuating cylinder and said sealing head actuating cylinders.

6. In a machine for sealing a bag or other flexible container filled with articles, the combination of a cradle having a bottom, side and end walls and an open top, one of said end walls and one of said side walls being connected hingedly to said bottom and movable outwardly to expand said open top to facilitate the reception of a filled bag into said cradle and for the dis-

charge of the bag from said cradle after it is sealed, said hinged side and end walls also being movable inwardly to engage the filled bag and to hold it in desired shape while it is being sealed, devices carried on said cradle for locking said hinged side and end walls in closed position, a movable support for said cradle, and means operable against said cradle through the movement of said support for shifting said cradle into various positions including positions for receiving, sealing and discharging the filled bag.

7. In a machine for sealing a bag or other flexible container filled with articles, the combination of a cradle having an open top and a plurality of movable walls, said movable walls, being expandable to facilitate the reception and discharge of a filled bag into and out of said cradle, said walls also being contractable to engage a filled bag and to hold it while it is being sealed, a movable support for said cradle, means for moving said support through a cycle of operation, tilting means connecting with said cradle and actuated by said support to swing said cradle into different positions including positions for receiving, sealing and discharging the filled bag, and devices carried on said cradle for simultaneously locking the movable walls of the cradle in contracted position and for starting the cycle of operation of the means for moving said support.

8. In a machine for sealing a bag or other flexible container filled with articles, the combination of a frame, a movable support mounted on said frame, a cradle pivotally carried on said support for receiving and holding a filled bag, means for moving said support, means operable against said cradle through the movement of said support for shifting said cradle into various positions including angularly disposed receiving and discharging positions and an upright sealing position, a plurality of parallelogram links pivotally carried on said frame and a sealing head unit carried on said parallelogram links and movable longitudinally relative to said cradle when the latter is in upright position for sealing the bag held in said cradle.

9. In a machine for sealing a bag or flexible container filled with articles, the combination of a frame, two sets of parallelogram links pivotally carried on said frame, a movable support carried on one set of said parallelogram links, a cradle pivotally carried on said support for receiving and holding a filled bag, means for moving said support, a tilting link connecting with said cradle and said frame for tilting said cradle with the movement of said support member into various positions including angularly disposed receiving and discharging positions and an upright sealing position, a sealing head unit carried on the other of said sets of parallelogram links and movable longitudinally relative to said cradle when the latter is in upright position for sealing the bag held in said cradle, and means controlling the actuation of said sealing head unit and the means for moving said support for synchronizing their cycles of operation.

10. A machine for sealing a filled bag or other flexible container, comprising a fixed frame having a support movably mounted thereon, a cradle tiltably mounted on said support for receiving and holding a filled bag, means for moving said support in opposite directions respectively for receiving and sealing said bag, actuating means connecting said cradle to said frame and cooperating with said moving means to tilt the cradle into bag receiving position when said sup-

port is moved in one direction and into bag sealing position when the support is moved in the opposite direction, a sealing head movably mounted on said frame, and means for moving said head into sealing engagement with said bag when the cradle is in sealing position.

11. A machine for sealing a filled bag or other flexible container, comprising a fixed frame having a support movably mounted thereon, a cradle tiltably mounted on said support for receiving and holding a filled bag, means for moving said support in opposite directions respectively for receiving and discharging said bag and for holding and sealing said bag, actuating means connecting said cradle to said frame and cooperating with said moving means to tilt the cradle into bag receiving and discharging position when said support is moved in one direction and into

bag holding and sealing position when the support is moved in the opposite direction, a sealing head movably mounted on said frame, and means for moving said head into sealing engagement with said bag when the cradle is in bag holding and sealing position.

AUGUST E. ALMGREN.
